UNITED STATES PATENT OFFICE.

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS.

CIRCULATING HEATER.

Application filed August 15, 1927. Serial No. 212,875.

My invention relates to a heating device and particularly to a hydrocarbon burning heater. One purpose is to provide a simple, convenient, compact burner and heater for 5 home use. Another object is the provision of such a heater which may be safely employed in a dwelling or a room which may safely be closely approached. Other objects will appear from time to time in the course 10 of the specification and claims.

I illustrate my invention more or less diagrammatically in the accompanying drawings, wherein—

Figure 1 is a perspective view;

15 Figure 2 is a vertical section taken along the line 2—2 of Figure 1;

Figure 3 is a plan view; and

Figure 4 is a detail showing the supporting structure;

20 Figure 5 is a detail of the door.

Like parts are indicated by like symbols throughout the specification and drawings.

A A^1 are angle iron frame members herein shown as forming a square or rectangle with 25 the supporting legs A^1 at the corners. A^2 are transverse supporting members upon which is seated the burner proper which in the particular form herein shown includes a base member generally indicated as B. The 30 base member has a more or less concave bottom portion B^1 surrounded by the cylindrical upwardly projecting wall B^2 from which outwardly projects the circumferential flange B^3 . B^4 is a centering flange upwardly projecting from the flange B^3 . The upper edge 35 of the wall B^2 is circumferentially channeled as at B^5 . B^6 indicates a lower closure member or shield, spaced beneath the burner base member B and supported on any suitable 40 means, for example upon the frame members A^2 by means of the securing bolts B^7 and spacers B^8 . It is centrally apertured as at B^9 , about the lower enlargement or fuel inlet G^5 of the base B, to which is connected 45 the fuel inlet pipe G^1 . The circumferential flange B^3 of the burner member B is provided with air inlet apertures B^{11} .

Mounted on the flange B^3 and centered by the flange B^4 is the outer drum C. Seated in 50 the channel B^5 is the inner drum C^1 which is provided with a number of primary air apertures C^2 and has about its upper edge a single row of upwardly and inwardly inclined secondary air apertures C^3 , herein 55 shown as of greater diameter than the pri-

mary air apertures. Seated on the upper edge of the drum C^1 and extending outwardly over the upper edge of the drum C is the closure ring C^4 with the lower centering flange C^5 and the upper centering flange 60 C^6 . Positioned thereupon and centered by the flange C^6 is the upper drum C^7 which forms a combustion and radiation chamber. It is provided with a cover C^8 , herein shown as convex and a flue passage C^9 in communication with the chimney C^{10} . 65

Mounted on the channel members A is an outer housing formed of the metal sheets D and the reinforcing and connecting corner angle irons D^1 . Said housing may be pre-assembled and may be spot welded or otherwise secured together if desired. D^2 indicates a cover member therefor having a plurality of transverse air outer apertures D^2 . The side members D may be provided with 70 any suitable air inlet apertures and I illustrate an air inlet member including a sheet of metal D^4 provided with the ledges D^5 beneath and between which air may flow. The forward member D is cut away as at D^6 to 75 admit the passage therethrough of the inlet member C^{10} outwardly projecting from the drum C^7 . It is provided with any suitable door C^{11} . Referring to Figure 5 C^{12} is a perforated piece, or netting, or any other 80 suitable member, having a large number of relatively small holes. C^{13} is a shield member 85 partially blocking off said perforated member, but penetrated by a cruciform aperture C^{14} . 90

Positioned between the drums C and C^7 and the housing member D is an intermediate shield or housing member E, preferably open at top and bottom in order to permit a free flow of air therethrough about 95 the cylinder C and C^7 .

In order to supply fuel to the burner I may employ one or more fuel tanks G, preferably two, in the form herein shown. The details do not of themselves form any part 100 of the present invention. Both tanks preferably feed to a single fuel inlet pipe G^1 closed by a valve G^2 controlled by the valve rod G^3 adapted to be axially moved by rotation thereof by means of the handle or lever G^4 . G^5 is a fuel inlet adapted to receive fuel along the line G^1 and to deliver it to the bottom portion B^1 of the burner. 105

An important feature of my device is the employment of the inflowing air to cool the 110

bottom of the burner, including the mixing chamber bottom B and the supports therefor, and to prevent overheating the floor. I am able to employ my circulating heater 5 in dwelling rooms, over wood floors or even over carpets without damage, owing to the fact that the normal inflow of air, upward about the mixing chamber and through the space between the members B and B⁶ has 10 a cooling and heat insulating function. This obviates the using of an insulating support or pad, as is the practice for example with the old line coal burning stoves or heaters.

15 It will be realized that whereas I have described and shown a practical and operative device nevertheless many changes might be made in the size, shape, number and disposition of parts without departing from 20 the spirit of my invention. I, therefore, wish my description and drawings to be taken as in a broad sense illustrative and diagrammatic rather than as limiting me to my specific showing.

25 The use and operation of my invention are as follows:

I have developed a practical and operative domestic heater which may burn a liquid or gaseous hydrocarbon. I have 30 herein shown my invention as embodied in a device for burning a liquid hydrocarbon.

In the operation of my burner as herein shown a liquid hydrocarbon is supplied to the lower portion B¹ of the burner. It receives a primary air supply through the apertures C², the hydrocarbon being vaporized or gasified in response to the radiant heat of the combustion taking place above. I so proportion the holes C², or otherwise 40 control the primary air supply, as to form a relatively completely hydroxylated mixture. This mixture is incombustible, or receives insufficient air to support combustion, until it passes upwardly to the level of the secondary air apertures C³. Sufficient air to support combustion is thereby supplied and the mixture is burned off, combustion taking place largely within the drum C⁷. The air supply passes upwardly between the supporting members A², the bottom of the stove 50 assembly being open, and the flange B³ being suitably cut away or formed to permit air to flow into the space between the drum C and C¹. The waste products of combustion pass outwardly along the flue C⁸ in the usual manner.

Instead of exposing the drum C⁷ and permitting the air of the room to be heated by radiation I prefer to circulate the air of 60 the room through a restricted space about the heater. The cold air from the bottom of the room is drawn upwardly through the open supporting frame and passes upwardly along the outside of the drums C and C⁷. 65 As it passes therealong it is heated and the

heated air escapes through the apertures D⁸ of the top of the housing. By employing the circulation principle a relatively small stove can heat a large volume of air and keeps the air in circulation, thus insuring 70 the adequate and even heating of large volumes of air and of a relatively large space. In the use of the commercial embodiment of my device, a single circulating heater may be employed to heat two or three adjacent 75 rooms and since the heated air is thoroughly circulated I avoid the overheating of a body of air about the stove and the consequent discomforts and disadvantages.

In order to cool the exterior housing and 80 to make it safe for use in dwelling I employ the intermediate open ended housing or screen E the interior of which may, if desired, have a reflective surface, in order to reflect back into the upwardly flowing 85 stream of air the heat received by it from the cylinder C⁷. Air will also flow upwardly through the space between the shield E and the housing members D but in order to prevent such upward stream of relatively 90 cool air from taking an unduly large relation to the total circulation of air I position the shield E relatively close to the members D, as shown in Figure 2. Further, to cool the place between the shield E and the members D I admit air as at D⁵, above the bottom edge of the shield E.

Referring to Figure 5 in the type of window employed the perforated metal or netting C¹² admits a slight amount of air, and thereby keeps itself clean from soot by the action of the air entering the small holes. The cross-shaped aperture is so designed that the frame can be observed either by squatting down and looking through the horizontal portion or else by bending over and looking through the vertical portion. It is a great advantage, and in fact almost essential, in a natural draft burner, that the flame be clearly seen while operating under 100 draft conditions. The perforated window above described is sufficient for this purpose and has the advantage, over the well-known mica windows, of being kept entirely free 105 from soot by the inflowing air.

110 I claim:

1. In a hydrocarbon heater, a combustion chamber and a door therefor, an observation window in said door and an air inlet member in said window having a plurality of small perforations, said perforations being arranged in the form of a cross.

2. In a hydrocarbon heater, a combustion chamber and a door therefor, an observation window in said door and an air inlet member in said window having a plurality of small perforations, and an additional member masking said air inlet member, said additional member having a cruciform aperture.

3. In a circulating heater a supporting 130

frame and feet therefor adapted to space such frame above the surface upon which the heater is supported, a mixing chamber supported by said frame and means for supporting a fluid fuel thereto, said mixing chamber being provided with a closed concave bottom portion, the bottom of said mixing chamber being spaced upwardly from said supporting surface, means for supplying air to said mixing chamber for the formation of a combustible mixture, and means for directing inflowing air about the bottom of the mixing chamber.

4. In a circulating heater a supporting frame and feet therefor adapted to space such frame above the surface upon which the heater is supported, a mixing chamber and means for supplying a fluid fuel thereto, the bottom of said mixing chamber being spaced upwardly from said supporting surface, means for supplying air to said mixing chamber for the formation of a combustible mixture, and means for directing inflowing air about the bottom of the mixing chamber, including a shield positioned beneath said mixing chamber and spaced therefrom and means for passing air through the space between the shield and the bottom of the mixing chamber.

5. In a circulating heater a mixing chamber and means for delivering a fluid fuel thereto, means for spacing said mixing

chamber upwardly from the surface upon which the heater is supported, said mixing chamber being provided with a closed concave bottom portion, means for delivering air to the mixing chamber and means for directing a flow of cool air, from without the heater, against said bottom portion.

6. In a circulating heater a mixing chamber and means for delivering a fluid fuel thereto, means for spacing said mixing chamber upwardly from the surface upon which the heater is supported, means for delivering air to the mixing chamber and means for directing a flow of cool air, from without the heater, against said bottom portion, including a shield positioned beneath the bottom of the mixing chamber and spaced therefrom, and an air inlet in said shield.

7. In a circulating heater, a supporting frame, a mixing chamber positioned therefrom, means for delivering a fluid fuel to the mixing chamber, means for circulating a cooling current of air about the exterior of the mixing chamber, and means for delivering air from such cooling current to the mixing chamber for mixture with the fuel therein.

Signed at Chicago, county of Cook, and State of Illinois, this 1st day of August, 1927.

JAMES L. BREESE, JR.
